(57) **CLAIM**

I claim the ornamental design for collapsible cell phone holder for a chair arm, as shown and described.

DESCRIPTION

FIG. 1 is a perspective view of the collapsible cell phone holder for a chair arm wherein the cell phone holder is collapsed.

FIG. 2 is a top view of the collapsible cell phone holder for a chair arm wherein the cell phone holder is collapsed.

FIG. 3 is a front view of the collapsible cell phone holder for a chair arm wherein the cell phone holder is collapsed.

FIG. 4 is a rear view of the collapsible cell phone holder for a chair arm wherein the cell phone holder is collapsed.

FIG. 5 is a left side view of the collapsible cell phone holder for a chair arm wherein the cell phone holder is collapsed. The right side view being a mirror image of the left side view.

FIG. 6 is a bottom view of the collapsible cell phone holder for a chair arm wherein the cell phone holder is collapsed.

FIG. 7 is a perspective view of the collapsible cell phone holder for a chair arm wherein the cell phone holder is extended.

FIG. 8 is a top view of the collapsible cell phone holder for a chair arm wherein the cell phone holder is extended.

FIG. 9 is a front view of the collapsible cell phone holder for a chair arm wherein the cell phone holder is extended.

FIG. 10 is a rear view of the collapsible cell phone holder for a chair arm wherein the cell phone holder is extended.

FIG. 11 is a left side view of the collapsible cell phone holder for a chair arm wherein the cell phone holder is extended.

FIG. 12 is a right side view of the collapsible cell phone holder for a chair arm wherein the cell phone holder is extended; and,

FIG. 13 is a bottom view of the collapsible cell phone holder for a chair arm wherein the cell phone holder is extended. The broken lines forming no part of the article.

1 Claim, 11 Drawing Sheets
